UNITED STATES PATENT OFFICE

142,153

DESIGN FOR AN INSOLE FOR A SHOE

Basil Darrell Huff, New York, N. Y., assignor to Knight Slipper Mfg. Corp., Brooklyn, N. Y.

Application May 29, 1945, Serial No. 119,801

Term of patent 7 years

(Cl. D7—5)

To all whom it may concern:

Be it known that I, Basil Darrell Huff, a citizen of the United States of America, residing in New York city, county of New York, and State of New York, have invented a new, original, and ornamental Design for an Insole for a Shoe, of which the following is a specification, reference being had to the accompanying drawing, forming part thereof.

Fig. 1 is a top perspective view of an insole for a shoe showing my new design.

Fig. 2 is a bottom perspective view thereof.

I claim:

The ornamental design for an insole for a shoe, substantially as shown.

BASIL DARRELL HUFF.
